SASH OPERATING MECHANISM

Filed Dec. 14, 1925

UNITED STATES PATENT OFFICE

EDWIN W. TERHUNE, OF IRVINGTON ON THE HUDSON, NEW YORK, ASSIGNOR TO
LORD & BURNHAM COMPANY, OF IRVINGTON ON THE HUDSON, NEW YORK, A
CORPORATION

SASH-OPERATING MECHANISM

Application filed December 14, 1925. Serial No. 75,331.

This invention relates to sash actuating mechanism, and relates particularly to mechanism for controlling the movement and position of comparatively heavy sashes hinged or hung from the top, such as are used in industrial structures or greenhouses, but it is understood that the invention is not limited thereto, but may be adapted to other structures and types of sash support.

10 Various types of sash operating mechanism have heretofore been used. These include the arm and rocker shaft type actuated by worm and gear, and the rack and pinion type also actuated by worm and gear. While 15 these types are well suited for certain conditions, they have certain limitations. When the former type is used for operating comparatively heavy sash to obtain substantial sash openings, the torsion on the shaft becomes excessive; this is particularly noticeable if the run of sash is of considerable length. Further, the sash is not held rigidly. In the rack and pinion type, as heretofore used, where one end of the rack bar is directly 20 pivotedly connected to the sash, it has required the rack bar used to be of a length at least as great as the opening required at the sash. Where the sash opening is large, this means that when the sash is closed, the end of 25 the rack bar extends within the building structure for a considerable distance. This is objectionable, particularly in structures where it is desired to place or store articles or objects adjacent to the wall or sash. A 30 further characteristic feature of the rack and pinion type of apparatus as heretofore used, is that it is necessary to make a comparatively large number of turns of the line shaft on which the pinions are mounted, to effect a 35 corresponding maximum opening of the sash. This consumes time and results in comparatively slow operation of the sash.

In the types of apparatus referred to, 40 where the main parts of the actuating mechanism, such as the worm and gear and the rack and pinion, have been provided to meet given conditions, the apparatus is not readily adapted to be adjusted or changed to meet 45 varying conditions of use requiring different

openings of sash, over varying runs, and in varying periods.

One of the objects of this invention is to provide sash operating mechanism which will overcome some of the limitations or objections above referred to. 55

A further object is to provide in sash actuating mechanism of the rack and pinion type, a means for obtaining a maximum movement of the sash to be effected with a minimum or 60 more restricted movement of the rack bar.

A further object is to provide in sash actuating devices of the rack and pinion type, a means such as a series of links or the like, interposed between the rack bar and the sash, 65 whereby the relative movement of the sash and rack bar and the relative force effective through the bar to open the sash to the different positions, may be readily changed or adjusted by varying the relative length and 70 points of pivotal connection of an arm or linkage mechanism, through which the movement of the rack bar is transmitted to control the movement and position of the sash.

Still a further object is to provide sash 75 operating mechanism of the type above referred to, wherein the sash is rigidly and positively held, and maintained in closed position by a direct inward thrust substantially normal to the sash.

A further object is to provide sash operating mechanism wherein the actuating mechanism is so disposed and arranged, when the sash is closed, as to permit storage or placing of articles or objects in the space near or adjacent to the line shaft or the actuating mechanism, without having the rack bar interfere with the articles there placed. Instead of projecting substantially inward from the inside face of the building wall or the sash, the rack bar is projected upward and outward. 85

Other objects and advantages will be apparent from the following description. For 90 purposes of illustration, one preferred form of the invention is shown in the accompanying drawings and described in the following specification.

Figure 1 is an elevation of a section of a 100

sash, showing the relative arrangement of the sash and actuating mechanism.

Figure 2 is a side elevation of Fig. 1, and shows in addition, the worm and gear and means for operating the same from below.

Figure 3 is a diagram showing a modified form in which the rack bar is under tension when the sash is opened, instead of being under compression as shown in Fig. 1.

As shown in the selected embodiment chosen for the purpose of illustrating one preferred form of the invention, a sash 10 is hinged or suspended from the top by a suitable hinge connection 11, 12, so as to permit the sash to swing outward and upward.

Suitable means are provided for controlling and effecting movement of the sash from below. A line shaft 19' is rotated by means of a worm 26 and gear 25, fixed on the shaft 19'. The worm and gear is shown within the casing 24, supported on a post 30. The worm is rotated by a chain 28, and sprocket mechanism 29, 31. The sprocket 31 is mounted on the worm shaft 27, and sprocket 29 is mounted on the post 30, and may be turned by the handle 32. The worm and gear serves as a stop or brake to hold the sash in any given position at all times.

The mechanism, capable of adjustment to different relative positions, for directly actuating the sash 10, includes a rack bar 18, and pinion 19, and a series of links or arms 14, 15, interposed between the rack bar 18 and the sash 10. The rack and pinion type of sash actuating device is particularly well adopted for long runs of sash, because of the relatively small torsion produced on the line shaft for any one sash. The pinions 19 are fixed on the line shaft 19', at points where it is desired to actuate the sash. A rack bar 18 is held in engagement with the pinion 19 by a suitable cradle 21, having rollers 22 engaging the outer edge of the bar 18.

The arm or link 14 is shown pivoted at one end 13' in a bracket 13 fixed to the sash frame or other stationary support. The link 14 is pivotally connected at another point 17 to a second link 15, which link is in turn also pivotally connected to the sash 10 through a suitable means such as a bracket 16'.

In the preferred form shown in Fig. 1 one end of the rack bar 18 is pivotally connected to the link 14 at a point intermediate its ends, and in such a position relative to the pinion 19 on the shaft 19' that when the sash is closed, the rack bar 18 extends upward and outward, instead of directly inward of the structure as it would if it were directly connected at one end to the sash. This feature is one of importance when this mechanism is to be used in industrial buildings or other structures where space adjacent or near to the outer walls is valuable for storage or other purposes.

A further feature of importance and of

great advantage, obtained by interposing a series of arms or links between the rack bar and the sash, is, that it enables the travel of, and the force transmitted through, the rack bar, to be varied or adjusted so as to be either greater or less than that of the sash, by changing the relative lengths and points of pivotal connections of the links and the rack bar. This is a comparatively minor change, and may be made by using the other main parts of the apparatus. To the best of my knowledge, this has been impossible in prior installations of the rack and pinion type, where one end of the rack bar is directly connected to the sash.

As shown in Figure 1, when the sash 10 is closed, the link 15 is substantially normal to the sash, thus resulting in a straight inward thrust which is positively effective to hold the sash rigidly and firmly in closed position.

A modified form of the apparatus is shown in Fig. 3. The arm or link 14 is extended at an angle beyond the pivotal point 13' to include the arm 14', forming a bell crank effect. The rack bar 18' is connected to the arm 14' at 23. As shown in Fig. 3, the point of connection 23 with the rack is at a greater distance from the point 13' than the corresponding point 20 is as shown in Fig. 1. As shown in Fig. 3 the rack bar 18' will be under tension when the sash is open, and will thus not be subject to any buckling strains, and the distance between the end of the link 14' and the pinion will be a minimum. By such an arrangement, at the point of greatest load or stress, that is when the sash is opened or raised, the greater portion of the rack bar is subject to no strains whatever. As shown in Fig. 1 the rack bar is under compressive strains when the sash is raised. The arrangement of the rack bar as shown in Figure 3, also permits the rack bar to be drawn upward and outward when the sash is closed, thus preserving the adjacent space for storage or other purposes. The modified form shown in Fig. 3 wherein the rack bar is made a tension member, clearly illustrates the flexibility and importance of this invention in meeting different conditions and requirements. As heretofore used in raising sash, the rack bar has been a compression member.

While certain preferred forms of the invention have been shown and described, it is understood that various changes and modifications may be made by those skilled in the art, without departing from the spirit and scope of the invention.

What I claim is:—

1. In sash actuating mechanism, the combination of a horizontal line shaft, a sash pivotally mounted on a horizontal axis, a pinion on said line shaft, a rack bar actuated by said pinion and a plurality of links interposed between the rack bar and sash, one of said links being pivoted at a fixed point,

and a connection between the rack bar and said last named link, whereby a direct inward thrust through one of the links substantially normal to the sash is exerted through the pinion and rack bar to hold the sash firmly closed, and permitting substantially the entire rack bar to assume a position within the space above the line shaft and between said shaft and the sash frame, when the sash is closed.

2. In sash actuating mechanism, the combination of a line shaft parallel to the axis of rotation of the sash, a sash pivotally mounted, a pinion on said shaft, a rack bar actuated by said pinion, a compound link connection between said sash and the sash frame, said rack bar being connected with one of the links, the relative arrangement being such that the link connected to the sash is substantially normal to the sash when opened and closed, and such that the rack bar is above the line shaft and substantially parallel to the sash when closed.

3. In worm and gear actuated sash operating devices, the combination of a line shaft, a worm and gear for actuating said shaft, a sash pivotally mounted to rotate about an axis parallel with the shaft, a pinion on said shaft, a rack bar actuated by said pinion, a stationary support, a series of links connected between the sash and the support, the end of one of the end links being pivotally connected to the sash, and arranged to transmit the force from the pinion through the rack bar so as to exert a direct inward thrust to hold the sash tightly closed, and the end of the other end link being pivotally connected to the stationary support, said rack bar being pivotally connected to the link connected to the stationary support, whereby a limited movement of the rack bar will effect a relatively large sash opening, and whereby said worm and gear function as an automatic lock to hold the sash in any other position.

4. In sash operating devices of the rack bar and pinion type, in combination, a stationary support arranged between the top and bottom of the sash frame, a series of links connected between the sash and the stationary support, the link connection to the sash being arranged to exert a direct inward thrust substantially normal to the sash when closed, and a connection between the rack bar and the end link connected to the stationary support, said last named connection being so placed relative to the pinion that the rack bar extends upward in a substantially vertical position when the sash is closed.

5. In sash operating mechanism of the rack and pinion type, the combination of a stationary support, a sash, a plurality of links connected between the sash and the stationary support, a connection between the rack bar and the link connected to the stationary support, the relative arrangement of the links and rack bar being such that when the sash

is in closed position, a substantially direct inward force normal to the sash is effective through the link connected to the sash to hold the sash firmly in closed position.

In testimony whereof I affix my signature. 70
EDWIN W. TERHUNE.
